ATTORNEY.

UNITED STATES PATENT OFFICE.

WILLIAM F. BOSSERT, OF UTICA, NEW YORK.

DESIGN FOR A FUSE-BOX.

SPECIFICATION forming part of Design No. 29,344, dated September 13, 1898.

Application filed July 21, 1897. Serial No. 645,470. Term of patent 7 years.

To all whom it may concern:

Be it known that I, WILLIAM F. BOSSERT, of the city of Utica, county of Oneida, and State of New York, have invented and produced a new and original Design for Fuse-Boxes for Electrical Apparatus, of which the following is a specification, reference being had to the accompanying drawing, illustrating the same.

The figure of the drawing shows the fuse-box of my design in perspective.

The feature of the design consists of the form or configuration of the whole box, as shown, and including particularly the por-

tions shown in the interior of the form and arranged as shown.

15

What I claim is—

The design for a fuse-box as herein shown and described.

In witness whereof I have hereto affixed my signature, this 6th day of March, 1897, in 20 the presence of two witnesses.

WILLIAM F. BOSSERT.
